U.S. Cl. 204—73 R 7 Claims

ABSTRACT OF THE DISCLOSURE

Heptachloro and heptafluoroquinoline and isoquinoline are selectively dehalogenated by electrolytic reduction.

BACKGROUND OF THE INVENTION

Perchloroquinoline and perfluoroquinoline can be prepared by vapor phase halogenation as described by Tapii in U.S. 3,420,883 or as described by British Patents 1,151,862 or 1,155,965.

The dehalogenation of haloaromatics by electrolytic reduction is generally known. The application of such techniques to a particular polyhalogenated compound to obtain a predictable product, however, is not known because there are many places where electrolytic reduction could occur.

SUMMARY OF THE INVENTION

It has now been found according to the present invention that the electrolytic reduction of heptachloroquinoline, heptafluoroquinoline, heptachloroisoquinoline, heptafluoroisoquinoline or any of these compounds containing an inert substituent gives a selective dehalogenation. This process gives desirable compounds having biological activity as fungicides for fungi, such as rice blast.

The quinoline compounds subject to electrolysis in the invention are perchloroquinoline, perfluoroquinoline or either of these compounds containing a substituent which is inert under the electrolysis conditions. The electrolysis selectively removes the halogen from the 4 position and then from the 2 position. The inert substituents are substituted in any positions on the rings except for the 4 position when one chlorine is removed and in the 2 and 4 positions when 2 halogens are removed. Representative examples of inert substituents include alkyl, cyano, amino, lower alkylamino and alkoxy. Compounds with these substituents include: 3-methylhexachloroquinoline, 3-cyanoheptachloroquinoline, 2-dimethylaminohexafluoroquinoline and 5-methoxyhexachloroquinoline. Preferred in the invention is the reduction of perchloroquinoline and perfluoroquinoline, with the reduction of perchloroquinoline being especially preferred because of the demonstrated ease of reaction.

The isoquinoline compounds reduced in the invention are perchloroisoquinoline, perfluoroisoquinoline or either of these compounds containing an inert substituent. In the electrolysis, the halogen is selectively removed from the 1 position and then from the 4 position. The inert substituents are the same as those for quinoline and must be substituted in positions that do not interfere with the electrolytic reduction. Reduction of perchloroisoquinoline is preferred.

The desired electrolytic reduction of the invention is carried out by techniques that are generally known. These techniques are described below and exemplified in the specific embodiments. Broadly, the starting halogenated quinoline or isoquinoline is dissolved in a suitable solvent containing an electrolyte, the solution is added to an electrolysis cell and current is passed through the cell until the desired degree of reduction is obtained.

The concentration of the reactants in the electrolytic

2

cell may vary widely as different reactants and solvents are employed in the reaction. Reactant concentrations can be as high as their solubility will permit at the reaction temperature, with nearly saturated solutions being especially preferred.

5 The design of the electrolysis cell used in the present invention is not critical. Numerous electrolytic cells known in the art may be readily employed in the present invention. Preferred electrolytic cells have cathodes of mercury or lead. The anode may be essentially any chemically inert material with graphite and platinum being especially preferred. Such preferred cell may be arranged in any conventional design.

The electrolyte used in the present invention may vary 15 widely. Preferred electrolytes in the present invention are neutral or acidic salts. The use of salts of strong bases may be detrimental to the progress of the reaction because of the tendency of such electrolytes to enter into reactions with the halogens. Specific examples of preferred 20 electrolytes include sodium p-toluenesulfonate, sodium acetate, ammonium p-toluenesulfonate, ammonium chloride, ammonium fluoride, tetramethylammonium chloride, and hydrochloric acid, sulfuric acid, acetic acid or phosphoric acid used alone or in combination with ammonia or a tertiary amine. Especially preferred is the use 25 of ammonium acetate, H_2SO_4 , acetic acid or HCl as the electrolyte. The concentration of the electrolyte may vary widely as different reactant concentrations, electrolytes, current densities and cathode potentials are employed.

30 The solvent employed in the electrolysis solution may vary widely as different reactants are employed in the electrolytic dehalogenation. The solvent should dissolve all or most of the starting material and the electrolyte and should be inert or at least not detrimentally reactive under the electrolysis conditions. Solvents preferred in 35 the present invention include the lower alcohols, lower alkylene glycol monoalkyl and lower amides. Representative examples of these preferred solvents include: alcohols such as methanol, ethanol, isopropanol and isobutyl 40 alcohol; lower alkylene glycol monoalkyl and dialkyl ethers such as 2-methoxypropanol, ethoxyethanol, dimethoxyethane and 1,2-dimethoxypropane; and lower amides such as dimethylformamide and acetamide. These solvents of the present invention may be used either alone 45 or in such combinations that a conducting medium results. Preferred cell fluids contain up to about 30% by weight of water to assure proper solubility of the electrolyte.

In the operation of the electrolysis cell, the cathode 50 potential is usually maintained greater (in terms of absolute value) than -0.5 volt versus the standard calomel electrode, with cathode potentials of -1.0 to -2.2 volts being especially preferred. The applied voltage provided by the power source may vary widely depending upon 55 the IR drop of the reaction medium. The IR drop is preferably minimized to prevent overheating of the reaction cell.

The current density may preferably range from about 60 0.01-5 or more amp./in.² of electrode with 0.1 to 1.0 amp./in.² being especially preferred. At higher current densities, the selectivity of the reaction decreases; therefore, the current density should be adjusted to give the desired minimization of by-products.

The temperature of the electrolysis reaction may vary 65 widely. The temperatures may be varied to maintain the cell contents as a liquid phase with temperatures from about 0° to about 100° C. or more being preferred and temperatures of about 20° to about 80° C. being especially preferred.

The reduction is usually and most conveniently carried to less than 100% conversion to minimize the over-

reduction of the product under the reaction conditions. As a general rule, 70 to 95% of the reduction theoretically required gives the most favorable yields of the desired product with minimum by-product. After the electrolysis, the product may be isolated by any conventional method.

The products produced by the electrolytic reduction are useful fungicides, especially for rice blast and tomato late blight.

SPECIFIC EMBODIMENTS

Example 1.—Reduction of heptachloroquinoline

An electrolytic cell was constructed in a 400 ml. beaker. The cathode was a pool of mercury in the bottom of the beaker having a surface area of about 4 sq. in., the anode was a platinum plate enclosed in a glass cup with a fritted bottom and the electrodes were connected to a constant voltage power source. The cell was also equipped with a saturated calomel reference electrode. A solution of 7 g. of heptachloroquinoline in 100 ml. of 1,2-dimethoxyethane, 75 ml. of methanol and 15 ml. of 30% aqueous H_2SO_4 was added to the cell. The electrolysis was run between 58° and 65° C., the applied voltage was 20-30 volts, the cathode potential vs. the calomel electrode measured -0.64 to -0.75 volts and the current ranged between 1.2 and 1.5 amps. except that it was at 0.8 amps for a short period. The progress of the electrolysis was followed by periodic sampling of the cell fluid and the product isolated by solvent removal was analyzed by vapor phase chromatography (VPC) and mass spectroscopy. The results are shown in Table I.

TABLE I
Electrolytic reduction of heptachloroquinoline

Sample time, min.	Chloroquinoline, percent VPC		
	Hepta	2,3,5,6,7,8-hexa	3,5,6,7,8-penta
30	90	10	0
53	77.5	20	2.5
79	58.7	37	4.3
106	48.3	47.7	7.0
155	21.5	66.0	12.5
189	5.8	78.5	15.7

Example 2.—Reduction of heptachloroquinoline

An electrolysis cell was constructed in a rectangular polyethylene case equipped with a reflux condenser, calomel electrode, sample port and gas sparger for nitrogen. The cathode consisted of a vertical copper plate over which a flow of mercury was maintained during operation and two graphite anodes were placed on each side parallel to the cathode. The electrodes had a surface area of about 60 sq. in. and were placed about 1 cm. apart. Power for the cell was supplied by a potentiostat rated to deliver 40 volts and 30 amps.

In this electrolysis cell was placed a solution of 20 g. of heptachloroquinoline in 600 ml. of 1,2-dimethoxyethane, 500 ml. of methanol and 110 ml. of 30% aqueous H_2SO_4 . The cell was operated between 45° and 63° C. at an applied voltage of 3.8 volts initially and then after 10 minutes from 5.5 to 6.0 volts. The current ranged from 4.2 amps at the beginning to between 10.5 and 14.0 amps after 10 minutes while the cathode potential was -1.4 at the beginning and -2 to -2.2 volts thereafter. Mixing was obtained by sparging nitrogen into the liquid. Periodic samples of the cell fluid were removed, stripped of solvent and analyzed. The results of the electrolysis are shown in Table II.

TABLE II
Electrolytic reduction of heptachloroquinoline

Sample time, min.	Chloroquinoline, percent VPC		
	Hepta	2,3,5,6,7,8-hexa	3,5,6,7,8-penta
10	89.5	0	10.5
30	59.7	1.5	33.8
40	27.8	4.6	67.6
48	13.6	6.9	79.5

Example 3.—Reduction of heptachloroquinoline using an ammonium acetate electrolyte

In the cell of Example 2, a solution consisting of 20 g. of heptachloroquinoline, 600 ml. of 1,2-dimethoxyethane, 500 ml. of methanol, 75 g. of ammonium acetate and 125 ml. of H_2O was electrolyzed. The temperature ranged from 55° to 62° C., the applied voltage ranged from 2.5 to 3.0 volts, the cathode potential ranged from -1.3 to -1.55 volts and the current ranged from 1.8 to 2.7 amps. After 16 minutes, the electrolysis was stopped, an additional 25 g. of ammonium acetate in 10 ml. of water was added and the reaction was resumed. Periodic samples were analyzed. The results are shown in Table III.

TABLE III
Reduction of heptachloroquinoline

Sample time, min.	Chloroquinoline, percent VPC		
	Hepta	2,3,5,6,7,8-hexa	3,5,6,7,8-penta
10	82.5	13.0	4.5
30	55.5	36.3	8.2
50	21.3	64.0	14.7
65	8.8	71.2	20.0

Example 4.—Reduction of heptachloroisooquinoline

In the electrolysis cell of Example 1, a solution consisting of 5.0 g. of heptachloroisooquinoline, 70 ml. of 1,2-dimethoxyethane, 60 ml. of methanol and 7.5 g. of ammonium acetate in 10 ml. of H_2O was electrolyzed. During the electrolysis, two 5.0 g. portions of heptachloroisooquinoline were added to the electrolysis cell one at 30 and the other at 70 minutes. The electrolysis was conducted between 49° and 58° C., the applied voltage was 11-14 volts, the cathode potential was -1.5 to -2.0 volts and the current was 0.40 to 0.56 amps. The analysis of cell fluid samples taken at the times indicated (before further reactant addition) are shown in Table IV.

TABLE IV
Reduction of heptachloroisooquinoline

Sample time, min.	Chloroisooquinoline, percent VPC		
	Hepta	3,4,5,6,7,8-hexa	1,3,5,6,7,8-hexa
10	80.3	16.9	1.1
20	65.1	27.4	2.6
70	50.3	39.2	2.5
150	48.9	39.6	3.6
315	30.4	56.7	4.5
420	16.9	66.3	6.9

In the same manner as shown by the examples above, heptafluoroquinoline may be electrolytically reduced to selectively replace the fluorine in the 4 position with hydrogen and then selectively replace the fluorine in the 2 position. Also in the same manner heptafluoroisoquinoline can be selectively reduced to obtain a predominant mono-dehalogenated compound of 3,4,5,6,7,8-hexafluoroisoquinoline and this compound can be further electrolytically reduced to remove the fluorine in the 4 position.

I claim:

1. An electrolytic process for selectively removing halogen from the 4 position when present and then optionally from the 2 position in a halogenated quinoline and from the 1 position when present and then optionally from the 4 position in a halogenated isoquinoline selected from the group consisting of heptahaloquinoline, heptahaloiso-

quinoline, a hexahaloquinoline, and a hexahaloisoquinoline, said hexahalo compounds having no other substituent which is reactive in the process wherein halogen is fluorine or chlorine which comprises applying to the cathode an electrical potential of -0.5 to -2.2 volts measured against a saturated calomel electrode and a current density of about 0.01 to about 5 amperes/sq. in. of cathode surface to a solution of said compound in an organic solvent which solvent also contains a neutral or acidic electrolyte.

2. The process of claim 1 wherein the quinolines are selectively reduced.

3. The process of claim 2 wherein heptachloroquinoline is reduced.

4. The process of claim 2 wherein 2,3,5,6,7,8-hexachloroquinoline is reduced.

5. The process of claim 1 wherein the isoquinolines are selectively reduced.

6. The process of claim 5 wherein heptachloroquinoline is reduced.

7. The process of claim 5 wherein 3,4,5,6,7,8-hexachloroisoquinoline is reduced.
